Pauline Frémion

ATTORNEY

UNITED STATES PATENT OFFICE.

MAURICE FRÉMION, OF PARIS, FRANCE

FLUSHING DEVICE.

Application filed April 17, 1925, Serial No. 23,968, and in France July 4, 1924.

The present invention relates to flushing devices, and more particularly to devices of this character which are utilized in conjunction with a hermetically-sealed tank, wherefore in the water is subjected to a certain amount of pressure exerted by the air contained in the upper part of the tank.

In tanks of the above type, the compression of the air is effected by the feed water which is supplied under pressure to the tank from the main; and the objects of the invention include the provision of improved valve means for controlling the supply of feed water and also the subsequent flushing action. The invention further resides in the provision of an improved air valve which is opened shortly after the commencement of the flush by the suction action created in the casing, and which remains open throughout the flush to enable air from the outside to enter the casing and thence pass to the tank until equilibrium is established between the air pressure in the tank and the atmosphere. The air valve is automatically closed immediately the flush starts by the pressure created by the initial descent of the flushing water which drives the air ahead of it and forces a portion of it to act on and close the valve. The actual compression of the air in the tank is, of course, effected by the incoming feed water, when the water supply valve is opened after a flush has been completed.

An embodiment of the invention is illustrated in the accompanying drawing, the single figure of which is a vertical sectional view, with parts in elevation, showing the invention installed in a vertical conduit or casing that is interposed in the piping connecting the usual hermetically-closed water tank or reservoir and the bowl; representation of the latter elements being omitted, however, as not being involved in the actual invention and, hence, as unnecessary to its understanding.

According to the present disclosure, the aforesaid casing, which takes the form of a tap and is generally designated I, comprises an upper cup-shaped portion I' which is internally threaded at its upper end to receive, in this instance, a regulator K that is connected to the bottom of the tank T. The regulator is constructed to permit communication between the interior of the tank and the cup; but it forms no part of, and is not essential to, the invention and it is usually

replaced by a pipe connection of some character which is threaded at its lower end into the cup and which likewise provides for communication between the aforesaid parts. 60

The cup I' has formed on one side a lateral nipple J to which is connected a pipe (not shown) that supplies water under pressure from the main, and in this nipple there is mounted a horizontal tube H that opens into a housing G arranged centrally of the cup. Housing G is open at its bottom and has slidably fitted in it a valve member comprising upper and lower heads D, D', an intermediate grooved or recessed portion F and 70 a closure shoulder E for coaction with the housing so that the position of the valve thus controls communication between tube H (and, hence, the water supply through nipple J) and the interior of the cup. The upper head D of the valve is disposed some distance below the top of the housing, the intervening space being designed to receive a certain amount of water which is utilized to take up the play of the valve. 75

The aforesaid valve (which will hereafter be termed the water supply or inlet valve) constitutes the upper part of a main valve A, which latter controls the flush and is slidably fitted in the neck portion I³ of casing I, such neck being located between the cup I' and the lower discharge portion or spout I² of the casing. Valve A normally occupies a lowered or closed position in neck I³ so as to shut off communication between the cup 90 and spout and thus prevent flushing from taking place. It is adapted to be raised from this position (which it resumes automatically by gravity) in order to permit the flush by means of a cam or eccentric sleeve 95 C whereon it constantly rests at its lower end; this cam sleeve being mounted on a horizontal shaft B' which is journaled in the upper part of the spout I² and is operated by an external handle B. 100

Assuming, then, that the various parts occupy the normal position represented in the drawing, with the valve A closed and the inlet or supply valve D, D' open, water will flow through the nipple J and tube H and into the groove or recess F whence it passes into the cup I', as shoulder E is then spaced from the housing G. Consequently, the cup will first be filled and then the water will flow upwardly through the regulator K (in this instance), or through the connecting pipe if used instead of the regulator, into

the tank which, as previously stated, is hermetically sealed, so that the entrance of the water will serve to place the air in the tank somewhat under pressure. When handle B 5 is operated to raise valve A into open position, the valve D, D' is likewise raised and, hence, shuts off the supply of water to the cup, the flush then taking place with the required force due to the elevation of the tank 10 and to the pressure of the air therein upon the water. It is to be understood that the position of the valve unit A—D, D' depends solely upon that of the cam sleeve C—in other words, upon the handle B—so that the 15 duration of the flush is thus placed entirely under the control of the operator who may manipulate the handle at will to raise or lower the valve unit.

In order to regulate the supply of air to 20 the tank for the purpose of maintaining the desired pressure therein, an automatic valve-controlled device may be provided; such device preferably comprising a plug K' which is threaded into an opening in the enlarged 25 upper portion of the spout I² of the casing and which is itself formed with a threaded seat to receive the reduced end of a smaller plug M. The latter plug is provided with a cap O having an inlet port 30 P, and is further provided at its inner side with a valve seat N' for a conical valve N, the stem of which projects outward through a bore or passage M' of substantially larger diameter formed in the plug. The main 35 plug K' is formed with an axial bearing opening wherein one end of shaft B' is journaled, and in the wall of this opening there is cut a spiral air passage L leading at one end to the interior of spout I² and 40 at the other end to the interior of the valve seat N'.

Due to the above-described arrangement, it will be apparent that when a flush occurs, the passage of the water through spout 45 I² will set up or create a suction action or partial vacuum therein, the effect of which will be to draw valve N in the direction indicated by arrow f' into open position, whereupon air flows through port P, passage M', seat N' and passage L into the interior of the casing, whence it passes into the tank and is finally compressed therein by the water. The air valve N will remain open throughout the duration of the 50 flush (in fact, it will not be closed until the next flush is initiated, as hereafter explained), and during this time air will continue to flow into the casing and thence into

the tank until equilibrium is established between the pressure in the tank and the atmosphere. The passage of the air to the cup is, of course, permitted since the valve A remains in open, raised position until the operator releases the handle. It is further to be understood that the descent of the water through the spout incidental to a flush first of all drives the air ahead of it, and forces some of it outward through passage L so as to close valve M; the suction action and resultant opening of the valve occurring slightly later. Also, the compressing of the air in the tank by the in-coming water does not take place until the flush has been completed and the compound valve restored to its normal position to close the main valve part A and open the water-supply part D, D'.

I claim as my invention:—

1. A flushing device, comprising a casing, a flushing valve therein, an operating member for said valve, and an automatically-operating means under the control of the flush for admitting air into the casing; said air-admitting means embodying a plug mounted in the casing and provided with an aperture that communicates at one end with the atmosphere and opens at its other end into a valve seat, and also with a spiral passage that communicates at opposite ends with the interior of the casing and the valve seat, and a valve in said aperture movable into and out of said seat to control the passage of air through the aperture into the casing.

2. A flushing device, comprising a casing having a tubular water inlet extending into the interior thereof and adapted for connection to a source of water supply under pressure, said inlet having its inner end enlarged vertically to form a housing which is open at its lower end; a valve unit embodying a valve member slidably fitted in said housing to control the passage of the water through the inlet and a separate valve member to control the flush; the water inlet valve member comprising spaced upper and lower heads, an intermediate grooved portion and a shoulder below the lower head for closing the open end of the housing; and a member cooperating directly with the flushing valve member for operating the valve unit bodily.

In testimony whereof I affix my signature.

MAURICE FRÉMION.
